BUTTON SEWING MACHINE

Franklin A. Reece, Brookline, Mass.

Original application March 26, 1940, Serial No. 325,983. Divided and this application January 9, 1943, Serial No. 471,861

12 Claims. (Cl. 112—112)

This invention relates to button sewing machines, and the present application is a division of a prior application filed March 26, 1940, Serial No. 325,983.

More particularly, the invention relates to machines for sewing on substantially flat buttons having perforations or holes through which the attaching thread is passed, especially, although not exclusively, "four-hole" buttons, that is to say, buttons having two pairs of holes and which are attached by two groups of stitches passing, respectively, through the several pairs of holes. In one type of machine for sewing four-hole buttons, it has heretofore been customary to impart to the needle a lateral jogging motion (in addition to its vertical reciprocation) in order to cause it to pass alternately through the holes of one pair, after which the work is shifted horizontally in a direction transverse to that of the jogging motion to bring the other pair of holes into position for cooperation with the needle. In another type of machine, the needle is caused to reciprocate in a fixed path and both the lateral jogging and longitudinal shifting movements are imparted to the work. Both types of machines require the provision of work clamps (including members engaging the work both above and below) and instrumentalities for moving the same, and in all such machines of which I am aware it has been necessary to locate these instrumentalities, at least in part, in the space between the overhanging arm or head and the bed of the machine, or beneath said bed, or both thereby obstructing the space available for the reception of the work and making it difficult, if not impossible, to attach buttons elsewhere than closely adjacent the edge of the material, as well as making difficult and inconvenient the adjustments necessary to varying requirements. Moreover, the location of the work moving instrumentalities beneath the bed requires a work supporting element of heavy construction and irregular form, as hereinafter further pointed out, which interferes with the convenient positioning of the work. These difficulties are also characteristic, to some extent at least, of machines for sewing two hole buttons in which the lateral jogging movements are imparted to the work.

The present invention has for its object to overcome this difficulty by providing a work clamp and operating mechanism therefor of such character that all of its parts can be so located as to be readily accessible for adjustment or otherwise without disturbing the work and leave between the head and the bed of the machine an unob-

structed space wherein a considerable quantity of goods can be gathered, thereby making it possible to attach a button (for example, a pocket or trimming button) at a considerable distance from the edge of the goods, and otherwise to facilitate the initial positioning and subsequent rearrangement of the work.

The invention will best be understood from the following description of a preferred embodiment thereof illustrated in the accompanying drawings, this, however, having been chosen for purposes of exemplification merely, as it will be obvious that the invention, as defined by the claims hereunto appended, can be otherwise embodied and used without departure from the spirit and scope thereof.

In said drawings:

Fig. 1 is a view, partly in side elevation and partly in longitudinal vertical section, of a button sewing machine having the invention incorporated therein.

Fig. 1a is a development of the cam for causing the needle to pass successively through two holes in the button.

Fig. 2 is a front elevation partly broken away.

Fig. 3 is a horizontal section taken substantially on the line 3—3 of Fig. 1.

Fig. 4 is a vertical section taken substantially on the line 4—4, Fig. 1.

Fig. 5 is a fragmentary horizontal section taken substantially on the line 5—5, Fig. 4.

The invention is herein shown as incorporated in a button sewing machine the frame of which comprises a hollow base 20 (Fig. 1) and a hollow stitching head including an upright portion 21 and an overhanging arm 22. Journalled in bearings in the arm 22 is a main or stitching shaft 23 adapted to be driven from any convenient source of power through a belt pulley 24 under the control of suitable automatic stop mechanism which may be substantially as fully described in application Serial No. 325,983, above referred to, but which constitutes no part of the present invention. Mounted for vertical reciprocation in the forward end of the arm 22 is a needle bar 25 carrying a needle 26, said needle bar being reciprocated by the shaft 23 through suitable connections, generally indicated at 27, and herein shown as of the type described in the Reece Patent No. 2,193,344, March 12, 1940.

Cooperating with the needle 26 is a rotary looper or hook 28 carried by a looper shaft 29 journalled in bearings in the base 20 and driven from the main shaft 23 by suitable power transmitting means, herein shown as a link belt or sprocket chain 30.

The rotary hook or looper may be of any usual form but as shown is of the ring type described in the Kohler and Lachman Patent No. 393,766, December 4, 1888, and supported and driven by devices such as those shown in the Bolton Patent No. 376,364, January 10, 1888.

The work plate 31 (which is located adjacent the top of the bed 20), for supporting the work W for the attachment of a button B, forms the lower, forwardly extending, horizontally disposed arm of a U-shaped clamp frame or yoke 32. The upper, overhanging, and likewise horizontally disposed and forwardly extending arm 310 of the frame 32 has a forward end portion 32a in which is guided a spring pressed presser foot bar 33 carrying at its lower end a button clamp, generally indicated at 34. The upper arm 310 of the frame 32 is provided with a lug 35 secured to a rock shaft 36 mounted to oscillate and move axially in bearings 37 depending from the overhanging machine frame arm 22. Oscillation of said shaft produces a lateral vibration of the frame 32 to cause the needle 26 to pass successively through different holes of a pair in the button B, while axial movement of said shaft causes a longitudinal movement of the frame 32 to position the button for the operation of the needle through different pairs of holes.

Oscillation of shaft 36, and consequent lateral vibration of the frame 32, is produced by a bell crank lever 38 (Fig. 2) fulcrumed on the shaft 36 and having a depending fork or yoke 39 embracing the forward end portion 32a of the upper arm 310 of the frame 32. The arm 40 of the bell crank 38 is connected by a link 41 with a lever 42 pivoted at 43 in the arm 22 and having a cam follower 44 alternatively engageable through openings 45 in said lever with cam grooves 46 and 47 in the side of a cam 48. The link 41 is connected with the arm 40 by a pivot 49 longitudinally adjustable in an arcuate slot 50 in the arm 40, whereby the amplitude of vibration of the frame 32 produced by the cam grooves 46 and 47 may be varied in accordance with the spacing of the holes in the button.

The cam 48 is formed with a worm gear 55 (Figs. 3 and 4) meshing with a worm 56 on the shaft 23, the gear ratio in the present instance being 24 to 1, so that the cam makes one complete rotation for each 24 reciprocations or thrusts of the needle, conveniently referred to as "stitches." As shown most clearly in Fig. 1a, each of the cam grooves 46 and 47 comprises sinuous portions 57 of such form as to cause the work and button holder to be moved alternately in opposite directions at each reciprocation, or between successive thrusts, of the needle, said sinuous portions being interrupted by straight portions 58 to cause the needle to pass twice, or make two thrusts, through the same hole in the button to form a tying stitch. In the construction shown, the cam groove 46 includes two straight portions 58 spaced 180° apart to cause a tying stitch to be formed during the last two of each twelve reciprocations or thrusts of the needle, thereby producing what may conveniently be called a twelve-stitch group, including and completed by a tying stitch, while the cam groove 47 includes three straight portions spaced 120° apart to cause a tying stitch to be formed during the last two of each eight reciprocations or thrusts of the needle, thereby producing an eight-stitch group likewise including and completed by a tying stitch.

The rock shaft 36 is moved longitudinally to position the work for sewing through the sev-

eral pairs of holes of a four hole button by means of a lever 63 (Figs. 1 and 5) having at its end a stud 64 engaging a circumferentially elongated opening in a collar 65 secured to said shaft 36. The lever 63 carries intermediate its ends a cam follower 66 adapted to engage a groove 67 in a cam 68 rotated from the cam 48 as hereinabove more particularly described. The cam groove 67 comprises two radially offset portions of equal length so that the work will be shifted from one pair of holes to the other in one direction or the other at each 180° movement of the cam 68. The lever 63 is fulcrumed on a stud 69 adjustable longitudinally of the lever to vary the axial movement imparted to the rock shaft 36 in accordance with the spacing of the pairs of holes in the button. The cam follower 66 comprises a pin slidably mounted in the lever 63 and connected by a lever 70 (see also Fig. 2) with a second similar pin 71 adapted to engage an opening in a lug 73 projecting inwardly from the frame and provided externally of the latter with an operating handle 72. By operating the handle 72 the cam follower 66 can be withdrawn from the cam groove 67 and the lever 63 locked to the frame to prevent any longitudinal shifting of the work in sewing a two-hole button.

Referring to Fig. 4, the cam 68 is keyed or otherwise secured to an upright shaft 95, journaled at its lower end in a bearing 96 in the lower wall of the arm 22 and at its upper end in a sleeve 97 clamped in a split hub 98 carried by an arm 99 formed on a ring 100 secured to the top of the arm 22 about an opening in the latter which is normally closed by a removable cap 101. The shaft 95 is formed with a key-way 102 to receive a sliding key 103 movable into upper and lower positions in either of which it is removably held by a spring-pressed locking pin 104 adapted to engage apertures 105 therein. When in its upper position, shown in Fig. 4, the key 103 engages a key-way 106 formed in the interior of the cam 48, so that the shaft 95 and cam 68 carried thereby are rotated directly by and in unison with the cam 48. When the key 103 is in its lower position, it engages a key-way 107 in a gear 108 rotatably mounted on the shaft 95 in a recess 109 in the cam 48. The gear 108 is formed with internal teeth 110 meshing with a pinion 111 journaled in the cam 48 and connected for rotation in unison with a coaxial pinion 112 likewise journaled in said cam and meshing with a fixed pinion 113, secured to or formed integral with the sleeve 97. The gear 108 and pinions 111, 112 and 113 constitute 3 to 2 gearing connecting the cams 48 and 68, so that when the parts are so connected, the shaft 95 and cam 68 will make one complete rotation for each movement of 240° of the cam 48. When the cam follower 44, Fig. 2, is engaged with the cam groove 46, Fig. 1a, of the cam 48, the cams 48 and 68 will be directly connected, through the shaft 95 and key 103, for rotation in unison, so as to cause a longitudinal shift of the work clamp at each rotation of 180° of the cam 48, and when the cam follower 44 is engaged with the cam groove 47, the cam 68 will be connected with the cam 48 through the 3 to 2 gearing described, so as to cause a longitudinal shift of the work clamp at each 120° rotation of the cam 48.

It will be seen that, in accordance with the invention as above described, all of the mechanism for producing the required movements of the work clamp assembly, including the adjustable

portions thereof, is associated with the overhanging arm 22 and is well above the bed 20, which, in connection with the U-shaped form of the frame or yoke 32, leaves a large and entirely unobstructed space A between the arm 22 and bed 20 at the rear of the combined presser foot and button clamp 34, so that a considerable quantity of the material W can be rolled or folded into said space, permitting positioning, on the work plate 31 and beneath the presser foot, of a portion of the work quite remote from the edges thereof. When, as in prior machines, the means for moving the clamp, including the portions which require adjustment to vary the amplitude of movement in accordance with the button being sewn, are located, even in part, beneath the bed, the necessary adjustments are difficult and inconvenient and involve interference with the work. In accordance with the present invention, by associating the clamp moving means wholly with the overhanging arm, and thereby locating the same wholly above the bed and work, the construction is simplified, its adjustment facilitated, and disturbance of the work avoided. This, in turn, is made possible by supporting the work clamping means as a unit from the overhanging arm whereby it can be wholly operated from the latter and is entirely free from any connection with the bed. Also, in machines having work moving instrumentalities located beneath the bed, it is necessary to connect such instrumentalities with the lower or work supporting element of the work clamp which, in turn, in order to provide the necessary strength and rigidity, requires a work supporting element of heavy construction and irregular shape, making relatively difficult the insertion of the work and its rearrangement between successive sewing operations. By supporting the entire work clamping assembly from the overhanging arm and associating all of its operating instrumentalities with the latter, in accordance with the present invention, the work supporting plate 31 is subjected to no operating strains, requires no direct connection with any of the operating instrumentalities, and can be made quite thin and flat, permitting the work to lie substantially flat on the bed throughout and greatly facilitating its positioning.

I claim:

1. In a button sewing machine, a frame comprising a bed and an overhanging arm, a needle and means for reciprocating the same in said arm toward and from said bed, means for clamping the work adjacent said bed, and means substantially wholly associated with said overhanging arm and located wholly above said bed for moving said work clamping means in two directions transverse to one another to change the position of the work with respect to the path of movement of said needle.

2. In a button sewing machine a frame comprising a bed and an overhanging arm, a needle, means for reciprocating the same longitudinally, a substantially U-shaped work clamp frame or yoke, one of the arms of said clamp frame constituting a work plate and the other being supported from said overhanging arm, a presser foot carried by the last named arm of said clamp frame and movable toward said work plate to clamp the work, and means for moving said clamp frame to change the position of the work with respect to the path of movement of said needle.

3. In a button sewing machine, a machine frame comprising a bed and an overhanging arm,

5 a needle and means for reciprocating the same in said arm toward and from said bed, a substantially U-shaped work clamp frame or yoke having a lower arm adjacent said bed and constituting a work plate and an upper arm adjacent to and supported from said overhanging arm, a presser foot carried by the upper arm of said clamp frame and movable toward said work plate to clamp the work, and means associated with said overhanging arm for moving said clamp frame to change the position of the work with respect to the path of movement of the needle.

10 4. In a button sewing machine, a machine frame comprising a bed and an overhanging arm, a needle and means for reciprocating the same in said arm toward and from said bed, a substantially U-shaped work clamp frame or yoke having a lower arm adjacent said bed and constituting a work plate and an upper arm adjacent to said overhanging arm, a presser foot carried by the upper arm of said clamp frame and movable toward said work plate to clamp the work, a rock shaft to which said upper clamp frame arm is secured, bearings carried by said overhanging arm and in which said rock shaft is mounted to oscillate and move axially, and mechanism associated with said overhanging arm for oscillating and axially moving said rock shaft.

15 5. In a button sewing machine, a frame comprising a bed and an overhanging arm, a needle and means for reciprocating the same in said arm toward and from said bed, means for clamping the work adjacent said bed, and means associated with said overhanging arm for moving said work clamping means in two directions transverse to one another to change the position of the work with respect to the path of movement of said needle, said last named means including means, located in said overhanging arm, for varying the amplitude of movement of said work clamping means in both directions.

20 6. In a button sewing machine, a frame comprising a bed and an overhanging arm, a needle and means for reciprocating the same in said arm toward and from said bed, work holding means supported as a unit from said overhanging arm and including means adjacent said bed for clamping the work to which a button is to be attached and for holding a button and positioning the same with respect to said work, and means associated with said overhanging arm and located wholly above said bed for moving said work holding means as a unit to change the position of the work and button with respect to the path of movement of said needle.

25 7. In a button sewing machine, a frame comprising a bed and an overhanging arm, a needle and means for reciprocating the same in said arm toward and from said bed, work holding means supported as a unit from said overhanging arm and including means adjacent said bed for clamping the work to which a button is to be attached and for holding a button and positioning the same with respect to said work, and means substantially wholly associated with said overhanging arm for moving said work holding means as a unit to change the position of the work and button with respect to the path of movement of said needle.

30 8. In a button sewing machine, a frame comprising a bed and an overhanging arm, a needle and means for reciprocating the same in said arm toward and from the bed, work holding means including means adjacent said bed for clamping the work to which a button is to be attached and

for holding a button and positioning the same with respect to said work, and means for moving said work holding means as a unit in two directions transverse to one another to change the position of the work and button with respect to the path of movement of the needle, said last named means including means, located wholly above the work, for varying the amplitude of movement of said work clamping means in both directions.

9. In a button sewing machine, a frame comprising a bed and an overhanging arm, a needle and means for reciprocating the same in said arm toward and from the bed, work holding means including means adjacent said bed for clamping the work to which a button is to be attached and for holding a button and positioning the same with respect to said work, and means substantially wholly associated with said overhanging arm for moving said work holding means as a unit in two directions transverse to one another to change the position of the work and button with respect to the path of movement of the needle, said last named means including means, located wholly above the work, for varying the amplitude of movement of said work clamping means in both directions.

10. In a button sewing machine, a main frame comprising a bed and an overhanging arm, a needle and means for reciprocating the same longitudinally, a clamp frame supported as a unit from said overhanging arm and including a portion located adjacent said bed and constituting a work plate, means carried by said clamp frame for clamping the work to which a button is to be attached to said work plate and for holding a

button and positioning the same with respect to said work, and means for moving said clamp frame as a unit to change the position of the work and button with respect to the path of movement of said needle.

11. In a button sewing machine, a main frame comprising a bed and an overhanging arm, a needle and means for reciprocating the same longitudinally, a clamp frame supported as a unit from said overhanging arm and including a portion located adjacent said bed and constituting a work plate, means carried by said clamp frame for clamping the work to which a button is to be attached to said work plate and for holding a button and positioning the same with respect to said work, and means substantially wholly associated with said overhanging arm and located wholly above said bed for moving said clamp frame as a unit to change the position of the work and button with respect to the path of movement of said needle.

12. In a button sewing machine, a main frame comprising a bed and an overhanging arm, a needle and means for reciprocating the same in said arm toward and from said bed, a clamp frame supported as a unit from said overhanging arm and including a thin, flat work plate adjacent the bed, said clamp frame having means for clamping the work to said work plate and for holding a button and positioning the same with respect to said work, and means substantially wholly associated with said overhanging arm for moving said clamp frame as a unit to change the position of the work and button with respect to the path of movement of said needle.

FRANKLIN A. REECE.
